(57) **CLAIM**

The ornamental design for a night light, as shown and described.

DESCRIPTION

FIG. 1 is a top, back perspective view of the night light; FIG. 2 is bottom, front perspective view thereof;

FIG. 3 is a back view thereof;

FIG. 4 is a front view thereof;

FIG. 5 is a right-side view thereof;

FIG. 6 is a left-side view thereof;

FIG. 7 is a top view thereof; and,

FIG. 8 is a bottom view thereof.

The dashed broken lines depict portions of the night light that form no part of the claimed design.

The diagonal shading on the top portion of the night light illustrates translucency.
